(57) **CLAIM**

The ornamental design for bottle, as shown and described.

DESCRIPTION

FIG. 1 is a front perspective view of a first embodiment of a bottle according to the design;
FIG. 2 is a front view of the bottle of FIG. 1;
FIG. 3 is a rear view of the bottle of FIG. 1;
FIG. 4 is a right side view of the bottle of FIG. 1;
FIG. 5 is a left side view of the bottle of FIG. 1;
FIG. 6 is a top view of the bottle of FIG. 1;
FIG. 7 is a bottom view of the bottle of FIG. 1;
FIG. 8 is a front perspective view of a second embodiment of a bottle according to the design;

FIG. 9 is a front view of the bottle of FIG. 8;
FIG. 10 is a rear view of the bottle of FIG. 8;
FIG. 11 is a right side view of the bottle of FIG. 8;
FIG. 12 is a left side view of the bottle of FIG. 8;
FIG. 13 is a top view of the bottle of FIG. 8; and,
FIG. 14 is a bottom view of the bottle of FIG. 8.

The broken lines depict portions of the bottle in which the design is embodied that are not considered part of the claimed design.

1 Claim, 14 Drawing Sheets

Matter enclosed in heavy brackets [ ] appears in the original patent but forms no part of this reissue; matter printed in italics indicates the additions made by reissue.
